G. E. LAMBERTY

AUTOMOBILE SIGNAL

Filed April 29, 1922

UNITED STATES PATENT OFFICE.

GEORGE E. LAMBERTY, OF OGDEN, UTAH.

AUTOMOBILE SIGNAL.

Application filed April 29, 1922. Serial No. 557,405.

To all whom it may concern:

Be it known that I, GEORGE E. LAMBERTY, a citizen of the United States, residing at Ogden, in the county of Weber and State of Utah, have invented certain new and useful Improvements in Automobile Signals, of which the following is a specification.

My invention relates to improvements in automobile signals, and has particular reference to such a signal embodying means whereby an electric lamp or lamps are caused to glow, when the speed of the machine exceeds a predetermined limit, thereby affording a visual signal that the speed limit is being exceeded.

An important object of the invention is to provide a device of the above mentioned character, which is characterized by an extreme simplicity, and is strong and durable.

Other objects and advantages of the invention will be apparent during the course of the following description.

In the accompanying drawings, forming a part of this specification and in which like numerals are employed to designate like parts throughout the same,

Fig. 1 is a plan view of a device embodying my invention,

Fig. 2 is a side elevation of the same, the circuit being shown diagrammatically,

Fig. 3 is a longitudinal section through the casing of the centrifugal switch, showing the weights in the inner position and the switch opened,

Fig. 4 is a similar view, with the weights swung outwardly, and the switch closed,

Fig. 5 is a transverse section taken on line 5—5 of Fig. 3, and,

Fig. 6 is a detail section through a binding post taken on line 6—6 of Fig. 3.

Fig. 7 is a diagrammatic view of the arrangement of the annular contact elements.

In the drawings, wherein for the purpose of illustration is shown a preferred embodiment of my invention, the numeral 10 designates the front wheel of an automobile, embodying a hub 11. This hub is rotatable upon the usual spindle of the axle, and this spindle is rigidly mounted upon a vertical shaft 12, pivoted within the forked end of the front axle 13. The vertical shaft is turned by a steering arm or crank 14, connected with the drag link 15, as is well known. This is the usual con-

struction present in the ordinary automobile.

My invention comprises a centrifugally operated switch device, embodying a casing 16, which is rigidly mounted upon a bracket 17, in turn clamped to the arm 14 by bolts 18 or the like. This casing is preferably formed of metal, while any other suitable material might be employed. The casing 16 has its ends closed by heads 18 and 19, which are also preferably of metal, and these heads are preferably sealed to the casing 16, by any suitable means, whereby access cannot be had to the interior of the casing 16 without detection. The purpose of this is to provide means whereby the centrifugal switch may be set or adjusted to close at a selected speed, and the driver of the car therefore cannot alter the speed at which the switch will close, without being detected, as will be more fully explained.

The centrifugally operated switch embodies a driving shaft 20, traveling through bearings 21, carried by the heads 18 and 19. The shaft 20, Fig. 1, extends outwardly, and has a gear 22, rigidly secured thereto, and this gear is in permanent mesh with a larger gear 23, secured to the wheel 10, adjacent its hub, by any suitable means. Of course the ratio of the gears 22 and 23 may be varied at will, so that the switch may be made to close at any selected speed, such as twenty-five miles an hour, more or less, as provided by the various regulation in different jurisdictions.

The centrifugal switch embodies a sleeve 24, loosely mounted upon the shaft 20 and provided at its forward end with a contact head or flange 25. The rear end of the sleeve 24 has an outwardly flaring flange 26, to engage with the inner ends of bell crank levers 27. These bell crank levers are provided at their outer ends with weights 28. The bell crank levers are pivoted at 29, upon a cross head which is rigidly mounted upon the shaft 20, and this cross head embodies a pair of radial bars 30, clamped to the shaft 20 at 31, and the bell crank levers are arranged between the ends of these bars and are pivoted thereto by the bolts 29. It is thus seen that as the cross head rotates, the weights 28 move outwardly, and the bell crank levers will force the sleeve 24 forwardly, and its forward movement is opposed by a compress-

ible coil spring 32, arranged in advance of the sleeve 24 and surrounding the shaft 20.

The numeral 33 designates a stationary contact, preferably in the form of a leaf spring, which is secured to the head 18 by a binding post or screw 34, and is thoroughly insulated from the head 18 by the insulating sleeve 35. The contact element 10 33 is so positioned that it is normally out of contact with the flange 25, but when the sleeve 24 is forced forwardly due to the action of the weights 28, contact 33 will engage the flange 25, and a circuit will be 15 closed, the parts 24 and 25 being of course metallic.

As more clearly shown in Fig. 2, the numeral 36 designates a source of current, one pole of which is connected with a wire 37, 20 which is connected with one terminal of an electric bulb 38, the other terminal of which is connected with a wire 39. The wire 39 is electrically connected at 40 with the head 18, and hence in electrical connection with 25 the contact flange 25. The binding post 34 is electrically connected with a wire 42, which is connected with the opposite pole of the source of current. It is thus seen that when the flange 25 engages contact 33, a 30 circuit will be closed to cause the lamp 38 to glow.

In this closed circuit, current flows from one pole of the source of current 36, through wire 37, wire 38, wire 39, head 18, shaft 20, 35 sleeve 24, flange 25, contact 33, wire 42 and back to the opposite pole of the source of current. It is therefore seen that when the car is driven at a speed in excess of a selected speed, that the lamp 38 will glow. 40 I contemplate arranging the lamp 38 in any desired conspicuous position upon the exterior of the automobile and I may mount the same upon the front left hand fender 43 of the automobile, while I may place the 45 lamp in any other desired position. It is preferred that the lamp 38 be of such a character that it is visible when glowing, from all sides thereof. The lamp may be of any color desired or required by various 50 locations.

The adjustment of the contacts so that the circuit will close at a selected speed is effected by means of an adjusting screw 43', passing through an opening in the contact 55 33 and engaging the head 18, but thoroughly insulated therefrom. It is obvious that the contact 33 may thereby be shifted or adjusted away from the flange 25.

The numeral 33' designates a second contact, similar to the contact 33, and adapted 60 to be connected with a circuit in a similar manner as described in connection with contact 33. By virtue of the large area of the flange 25 it will be seen that a number of 65 contacts 33 may be arranged in an annular

group about the shaft 20, and hence a corresponding number of circuits controlled by the centrifugal switch.

In the use of the device, it is installed upon the automobile as I have described. 70 The contact 33 is adjusted so that the circuit will close at a desired speed, and the heads 18 and 19 are secured to the casing and sealed thereto so that they cannot be removed without detection. The device 75 works entirely automatically, and when the car is driven beyond a selected speed, the bulb will glow.

It is to be understood that the form of my invention herewith shown and described 80 is to be taken as a preferred example of the same, and that various changes in the shape, form, size, and arrangement of parts may be resorted to without departing from the spirit of my invention or the scope of 85 the subjoined claims.

Having thus described my invention, I claim:

1. The combination with the steering mechanism of an automobile, including a 90 front wheel, and an arm connected with the front wheel to turn it in steering and retaining a fixed relation to the front wheel, of a horizontally arranged casing rigidly mounted upon the steering arm, a drive shaft within the casing and extending outwardly thereof, a gear mounted upon the outer end of the drive shaft, a second gear carried by the front wheel and permanently engaging the first named gear, a sleeve slide- 100 able upon the shaft and having a radial flange, a support carried by the drive shaft within the casing, bell crank levers pivoted to the support with corresponding ends thereof engaging the sleeve to move it in one direction, weights carried by the bell crank levers, a spring to oppose the movement of the sleeve in one direction, a contact arranged within the casing and adapted to engage with the contact flange when 105 the sleeve is shifted toward it, and a circuit connected with the contact including a source of current and a visual signal.

2. In a signal device for automobiles, the combination with the steering mechanism of 115 an automobile including the front wheel, and a steering arm connected therewith to shift the front wheel and having a fixed relation with respect thereto, of a substantially horizontal casing rigidly mounted upon the steering arm, a drive shaft mounted within the casing and extending outwardly there- 120 beyond, a gear mounted upon the outer end of the drive shaft, a second gear rigidly mounted upon the front wheel and permanently engaging the first named gear, a sleeve slide- 125 able upon the drive shaft and having a radial contact flange, a support carried by the drive shaft within the casing, bell crank levers pivoted to the ends of the 130

support to engage the sleeve and shift it in one direction, weights secured to the ends of the bell crank levers, a spring to oppose the movement of the sleeve in one direction, 5 and an annular series of contacts arranged within the casing and adapted to contact with the contact flange, each of said contacts being positioned different distances from the sleeve, whereby circuits may be closed at 10 different times.

3. In a signal device for automobiles, the combination with the steering mechanism of an automobile including a front wheel and steering arm to turn the same, said arm 15 bearing a fixed relation to the wheel, a casing rigidly mounted upon the steering arm, a rigid substantially horizontal shaft mounted within the casing, a gear rigidly secured to the outer end of the rigid shaft, a second 20 gear rigidly mounted upon the front wheel and permanently engaging the first named

gear, and a centrifugal circuit closing means mounted within the casing and driven by said rigid shaft. 1

4. In a device of the character described, 25 the combination with a casing, of a shaft mounted to rotate therein, a sleeve slidable upon the shaft and having a radial contact flange, a support rigidly mounted upon the shaft to rotate therewith, bell crank levers 30 pivoted upon the support and engaging the sleeve to shift it in one direction and carrying weights, a spring engaging the opposite end of the sleeve to oppose its movement in that direction, and a plurality of contacts 35 arranged at the end of the flange for engagement with the contact flange, said contacts being spaced different distances from the contact flange whereby circuits may be 40 closed at different times.

In testimony whereof I affix my signature.
GEORGE E. LAMBERTY.
